AMERICAN CAN COMPANY, OF NEW YORK, N. Y., A CORPORATION OF NEW JERSEY.

NOTCHING MECHANISM FOR CAN-BODY BLANKS.

1,020,550.

Specification of Letters Patent. Patented Mar. 19, 1912.

Application filed January 28, 1910. Serial No. 540,558.

To all whom it may concern:

Be it known that I, CHARLES W. GRAHAM, residing at Rome, in the county of Oneida, State of New York, have invented certain new and useful Improvements in Notching Mechanism for Can-Body Blanks, of which the following is a specification.

This invention relates to can forming machinery, and more particularly to a mechanism for treating the edges of a blank preparatory to forming the same into a can body.

More specifically stated, the invention relates to a mechanism for removing a part or parts of an edge or edges of a blank, preliminary to forming the same into a can body of a certain type.

One of the objects of the invention is to produce a device of the kind described, generally known as a notcher, which is particularly compact in its structural arrangement, and simple in the disposition and mode of operation of its parts.

Another object is to provide, in a device of the kind described, a die and a coöperating notcher having interengaging portions, whereby the operating parts will reciprocally guide one another.

Still another object is to mount the movable member of a die-and-notcher mechanism upon a shaft, making possible an efficient and economical drive with a minimum of operating parts, and subserving compactness.

A further and more specific object is to provide the parts of a die-and-notcher with portions embracing the operating shaft, one of the operating parts being rotatable with the shaft and with respect to the other parts.

A further object is to provide the die member of such a mechanism with spaced portions engaging a driving shaft, and the notcher member with a portion embracing the shaft between said spaced portions of the die member, one of said members, preferably the notcher member, being fast on the shaft.

I also aim to provide a shaft-driven and supported mechanism of the kind referred to, which is driven by practically direct and very simple connections with the main shaft of a can machine.

Furthermore, (and the attainment of this object is rendered possible by the disposition of parts indicated above) I aim to provide a notcher in which the operating parts are readily and simultaneously adjustable.

Other objects and aims of the invention, more or less broad than those above stated, together with the advantages inherent, will be in part obvious and in part specifically adverted to in the course of the following description of the elements, combinations and arrangement of parts constituting the invention, and the scope of the application thereof will be defined in the appended claims.

In the accompanying drawings, which are to be taken as a part of this invention, and in which I have shown a merely preferred form of embodiment of the invention as applied to a can making machine: Figure 1 is a vertical sectional view, partly elevation, of a can machine in which this invention is applied; Fig. 2 is a sectional plan view of the subject matter of Fig. 1; Fig. 3 is a front elevation, partly in section, of a notcher device embodying the invention, showing the immediate driving connections; Fig. 4 is a detail view of the notcher proper; Fig. 5 is a sectional view, partly in elevation, on the line 5—5 of Fig. 3; Fig. 6 is a section on the line 6—6 of Fig. 3; and Fig. 7 is a schematic plan view, partly in section, illustrating the relation of devices embodying this invention to the bed of a can body machine, along which blanks are fed into operative juxtaposition with said device.

Referring to the numerals on the drawings, 1 indicates the frame of a machine embodying various mechanisms necessary for different treatments of a blank, and for the orderly progression of the latter to each of said mechanisms. In a preferred machine I provide a main drive shaft 2, which may be actuated by means of a pulley 3 exteriorly of the machine.

4 indicates a bed arranged centrally of the machine, and 5 a reciprocating blank feed, which is adapted to move a blank intermittently along said bed, the reciprocating feed being preferably actuated by suitable connections with the drive shaft 2. In the movement of the blank along the bed it is

presented in turn to notching mechanisms 6 disposed at opposite sides of the bed 4, and which will be hereinafter more particularly described; thence to edging or hook forming 5 devices 7, arranged on opposite sides of the bed; and thence to a horn 8 about which it is bent by suitable mechanism into a can body. The edging means, the horn, and other parts of the machine are driven by 10 suitable connections with the drive shaft, but detailed description thereof, and of their relation to the machine, is deemed unnecessary for the purposes of this specification, and because the same may be found in a co- 15 pending application Serial No. 540,569 filed of even date.

Referring now more particularly to the notching mechanism, it should be understood that the purpose of this device is to 20 remove portions of a blank edge, in the form of a notch or incision, as is necessary in the manufacture of certain types of cans. To this end a blank is fed along the bed 4 edge-wise intermittently, so that one of its phases 25 of movement presents it in operative relation to the notching mechanisms 6, which are positioned in alinement at opposite sides of the bed. Here the notching mechanism, by properly timed actuations, operates to 30 cut a notch or notches in the presented edge portion of the blank. It is to be understood that while I have shown the notching mechanism at opposite sides of a machine operating on opposite edges of the blank, 35 they are adapted for use singly. And inasmuch as the mechanisms shown are substantially identical in construction, except for such differences as are due to their opposed relation in the machine, I shall describe but 40 one of them.

Each of the notcher mechanisms comprises a box-like casing 9, which is provided at opposite ends with bearings 11 and 12 for a shaft 14. At one end the said casing is 45 provided with a tubular extension 15 beyond the bearing 11, and the said shaft 14 projects into said tubular extension. Within said extension the shaft is provided with a pinion 16, and beyond said pinion there is 50 a closure 17 for the tubular extension. Preferably cast integral with the casing as thus far described is a sleeve 18, disposed transversely of the shaft bearings, and opening into the tubular extension. Within said 55 sleeve is adapted to reciprocate a rack rod 19, which engages the pinion 16, and in its reciprocation rocks the shaft 14.

The shaft 14 is provided with a longitudinal key-way 21 and within said key-way is 60 adapted to engage a correspondingly formed key 22 on a notcher member 24, which comprises an annular support or collar 25 adapted to be slid onto the shaft and having an integral, preferably segmental, cutting mem-

ber 26, which may be of any preferred cross-section, or as shown in the drawings. Closely embracing the member 25 are spaced collars 27 and 28, within which the shaft 14 is free to rotate, and preferably integral with said collars 27 and 28 is the die portion 65 70 29 of the mechanism. This die portion is preferably segmental in form, as indicated in Fig. 6, and abuts at its rear end against the lower part of the casing, to which it is secured as by means of a bolt 31. 75

From the description thus far given it is evident that the die portion 29 is fixed in the casing, while the notcher proper oscillates toward and from it, being retained in its working position by the collars 27 and 28. 80 The bolt fastening 31 for the die preferably passes through a slot 32 in the casing, and obviously upon loosening the bolt the die may be slid along the shaft, carrying the notcher with it, so that adjustments of the 85 die and notcher longitudinally of the shaft may be made simultaneously. I have shown each shaft provided with two of the dies and coöperating notchers, and only one set of them, indicated by the numeral 34 in Fig. 90 3, is adjustable in the slot 32, the fastening of the other being through ordinary bolt holes.

The die member 29 is provided with an aperture 35 extending therethrough from the face down, and a removable die plate 36 is carried on the face, being provided with a notch shaped conformably with the cross-section of the notcher part 26. It will be seen that as the shaft 14 is rocked, the 95 notcher 26, moving with the shaft, will approach the die 29, and cut out a correspondingly shaped piece from the edge of the blank which overlies the die. The cut out piece is forced through the notch in the removable die plate and thence falls through the aperture in the die. 105

It will be observed that the collar 25 is of slightly larger diameter than the guiding collars 27, 28, and that die-plate 36 is cut 110 out and disposed to snugly fit collar 25, so that engagement of notcher 26 with its notch in the die-plate may be at all times assured.

The rack rod 19 which drives the shaft 14, as already described, is reciprocated as by 115 means of a link 37 connected to an eccentric strap 38 which is driven from an eccentric 39 on a shaft 41 that extends transversely of the machine and which is driven by suitable connections with the main drive shaft in an 120 obvious manner.

In Fig. 1, I have shown the bed comprising two parts in longitudinal parallelism, but movable relatively to each other, as by means of supporting pinions 42, movable on 125 the frame of the machine. In this manner I am enabled to adapt the bed for the accommodation of different sized blanks. In view

of this adaptability the notchers should be adjustable toward and from each other on opposite sides of the bed, and to this end they may be carried on the sides of the bed, 5 as shown at 44 in Fig. 1. This attachment is preferably through the intermediary of a bracket 45, upon which the casing is held in adjustable relation by means of a bolt and slot connection indicated at 46 in Fig. 6.

10 If the bed members, with the attached notching device be moved, it will, of course, be necessary to move the eccentric 39 along the shaft.

As many changes could be made in the 15 above construction and many apparently widely different embodiments of my invention could be made without departing from the scope thereof, it is intended that all matter contained in the above description or 20 shown in the accompanying drawings shall be interpreted as illustrative merely and not in a limiting sense. It is also to be understood that the language used in the following claims is intended to cover all of the 25 generic and specific features of the invention herein described and all statements of the scope of the invention which, as a matter of language, might be said to fall therebetween.

30 Having thus described my invention, what I claim and desire to secure by Letters Patent is:

1. In a device of the kind described, a casing, a rock shaft mounted in the casing, 35 a die secured to the casing and forming a part thereof, a notching device upon said shaft within the casing coöperative with the die, said die and notching device having interengaging and mutually guiding portions and means for 40 rocking the shaft.

2. In a device of the kind described, a casing, a rock shaft mounted in the casing, a die secured to the casing and having a portion 45 in which the rock shaft has a bearing, and a notching device operated by the shaft within the casing coöperative with the die, said die and notching device having interengaging and mutually guiding portions and means for 50 rocking the shaft.

3. In a device of the kind described, a casing, a rock shaft mounted in the casing, a die secured to the casing and having spaced portions in which the shaft rotates, and a notching device operated by the shaft coöperative with the die and moving between 55 said spaced portions of the die, said die and notching device having interengaging and mutually guiding portions and means for rocking the shaft.

4. In a device of the kind described, a casing, a rock shaft mounted in the casing, a die secured to the casing and having a portion in which the rock shaft has a bearing, and a notching device operated by the shaft 60

within the casing coöperative with the die, 65 and means for rocking the shaft, said means including a pinion upon the shaft, said die and notching device having interengaging and mutually guiding portions and a means for driving the pinion. 70

5. In a device of the kind described, a casing, a rock shaft mounted in the casing, a die secured to the casing and having spaced portions in which the shaft rotates, and a notching device operated by the shaft coöperative with the die and moving between 75 said spaced portions of the die, and means for rocking the shaft, said means including a pinion upon the shaft, said die and notching device having interengaging and mutually guiding portions and a means for driving the pinion. 80

6. In a device of the kind described, a casing, a rock shaft mounted in the casing, a die secured to the casing and having a portion 85 in which the rock shaft rotates, and a notching device rotatable with said shaft, said die and notching device having interengaging and mutually guiding portions.

7. In a device of the kind described, a casing, a rock shaft mounted in the casing, a die secured to the casing and having a portion in which the rock shaft rotates, and a notching device rotatable with said shaft and adjustable longitudinally thereof, said 95 die and notching device having interengaging and mutually guiding portions.

8. In a device of the kind described, a casing, a shaft mounted in the casing, a die secured to the casing and forming a part 100 thereof, a notching device upon said shaft within the casing, said die and notching device having interengaging and mutually guiding portions and means for actuating the shaft. 105

9. In a device of the kind described, a casing, a shaft within the casing, a die and a notching device both supported by the shaft, and one of said last named members being driven by the shaft. 110

10. In a device of the kind described, a casing, a shaft within the casing, a die and a notching device both supported by the shaft, and both of said last named members adjustable on the shaft. 115

11. In a device of the kind described, a casing, a shaft within the casing, a die and a notching device both supported by the shaft, both of said last named members being adjustable on the shaft, and one of said members being driven by the shaft. 120

12. In a device of the kind described, a casing, a shaft within the casing, a die and a notching device both supported by the shaft, both of said last named members being adjustable longitudinally of the shaft. 125

13. In a device of the kind described, a casing, a shaft within the casing, a die and

a notching device both supported by the shaft, both of said last named members being adjustable longitudinally of the shaft, and one of said members being driven by 5 the shaft.

14. In a device of the kind described, a laterally adjustable casing, a shaft within the casing, a die secured to the casing and forming a part thereof, a notching device 10 upon said shaft within the casing, and means for actuating the shaft.

15. In a device of the kind described, a laterally adjustable casing, a shaft within the casing, a die and a notching device both 15 supported by the shaft, and one of said last named members being driven by the shaft.

16. In a device of the kind described, a laterally adjustable casing, a shaft within the casing, a die and a notching device both 20 supported by the shaft, and both of said last named members adjustable on the shaft.

17. In a device of the kind described, a laterally adjustable casing, a shaft within the casing, a die and a notching device both 25 supported by the shaft, both of said last named members being adjustable on the shaft, and one of said members being driven by the shaft.

18. In a device of the kind described, a 30 laterally adjustable casing, a shaft within the casing, a die and a notching device both supported by the shaft, both of said last named members being adjustable longitudinally of the shaft.

35 19. In a device of the class described, a laterally adjustable casing, a shaft, within the casing, a die and a notching device both supported by the shaft, both of said last named members being adjustable longitudinally 40 of the shaft, and one of said members being driven by the shaft.

20. In a device of the kind described, in combination, a casing, a rock-shaft within the casing, a die secured to the shaft and to 45 the casing, a notching device secured to the shaft and moving therewith, and a support to which the casing is adjustably secured.

21. In a device of the kind described, in combination, a casing, a shaft within the 50 casing, a die secured to the shaft and to the casing, a notching device secured to the shaft and moving therewith, said die and notching device being simultaneously adjustable on the shaft.

55 22. In a device of the kind described, in combination, a casing, a shaft within the casing, a die secured to the shaft and to the casing, a notching device secured to the shaft and moving therewith, said die and notching device being simultaneously adjustable longitudinally of the shaft.

23. In a device of the kind described, in combination, a casing, a shaft within the casing, a die secured to the shaft and to the

casing, a notching device secured to the shaft 65 and moving therewith, said die and notching device being simultaneously adjustable on the shaft, and a support to which the casing is adjustably secured.

24. In a device of the kind described, in 70 combination, a casing, a shaft within the casing, a die secured to the shaft and to the casing, a notching device secured to the shaft and moving therewith, said die and notching device being simultaneously adjustable 75 longitudinally of the shaft, and a support to which the casing is adjustably secured.

25. In a device of the kind described, in combination, a casing, a rock-shaft within the casing, a die secured to the shaft and to 80 the casing, a notching device secured to the shaft and moving therewith, and a support to which the casing is adjustably secured.

26. In a device of the kind described, in combination, a casing, a rock-shaft within 85 the casing, a die secured to the shaft and to the casing, a notching device secured to the shaft and moving therewith, said die and notching device being simultaneously adjustable on the shaft. 90

27. In a device of the kind described, in combination, a casing provided with bearings in its end walls, a shaft mounted in said bearings, a die having spaced bearings on the shaft and provided with an aperture, 95 a notching device secured to the shaft and working between said spaced bearings of the die, a pinion upon the shaft, and means for driving the pinion.

28. In a device of the kind described, in 100 combination, a casing provided with bearings in its end walls, a shaft mounted in said bearings, a die having spaced bearings on the shaft and provided with an aperture, a notching device secured to the shaft and 105 working between said spaced bearings of the die, a pinion upon the shaft, means for driving the pinion, and means for adjusting the die and notcher upon the shaft.

29. In a device of the kind described, in 110 combination, a casing provided with bearings in its end walls, a shaft mounted in said bearings, a die having spaced bearings on the shaft and provided with an aperture, a notching device secured to the shaft and 115 working between said spaced bearings of the die, a pinion upon the shaft, means for driving the pinion, and means for adjusting the die and notcher longitudinally of the shaft. 120

30. In a device of the kind described, in combination, a casing, a shaft in the casing provided with a longitudinal key-way, a die and a notcher having bearings on the shaft, and one of said two last named elements having a key engaging said key-way. 125

31. In a device of the kind described, in combination, a casing, a shaft on the casing

provided with a longitudinal key-way, a die and a notcher having bearings on the shaft, one of said two last named elements having a key engaging said key-way, and a support to which the casing is adjustably secured.

32. In a device of the kind described, in combination, a casing, a shaft in the casing provided with a longitudinal key-way, a die having a bearing on the shaft, means for holding the die against movement with the shaft, a notcher coöperative with the die having a bearing on the shaft and provided with a key engaging said key-way.

33. In a device of the kind described, in combination, a casing, a shaft in the casing, a die and a notcher both having bearings on the shaft, means for preventing rotative movement of one of said two last named members, and means for securing the other member to the shaft.

34. In a device of the kind described, in combination, a shaft in the casing, a die and a notcher both having bearings on the shaft, means for preventing rotative movement of one of said two last named members, and means for securing the other member to the shaft, said die and notcher having interengaging parts adapted to maintain them in proper relation.

35. In a device of the kind described, in combination, a bed, a casing adjacent the bed, a shaft in the casing, a notcher mounted on the shaft, and means for actuating the shaft, including an eccentric.

36. In a device of the kind described, in combination, a bed, a casing adjacent the bed, a shaft in the casing, a notcher mounted on the shaft, a pinion on the shaft, and means for driving the pinion including an eccentric.

37. In a device of the kind described, in combination, a bed, a casing adjacent the bed, a shaft in the casing, a notcher mounted on the shaft, a pinion on the shaft, a rack-rod engaging the pinion, and means for moving the rack-rod, including an eccentric.

38. In a device of the kind described, in combination, a casing, a shaft mounted therein, a die comprising spaced collars embracing the shaft and within which the shaft is rotatable and a die portion secured to the casing, a notching device comprising a collar fixed to the shaft and moving with the shaft between said spaced collars of the die, and a notching member on said collar.

39. In a device of the kind described, a casing, a shaft mounted therein, a die comprising spaced collars embracing the shaft and within which the shaft is rotatable, and a segmental die portion secured to the casing, a notching device comprising a collar fixed to the shaft and movable therewith between said spaced collars of the die, and

a notching member removably secured to said collar.

40. In a device of the kind described, a casing, a shaft mounted therein, a die comprising spaced collars embracing the shaft and within which the shaft is rotatable, and a die portion integral with said collars secured to the casing, a notching device comprising a collar on the shaft and rotatable therewith between said spaced collars of the die, and a notching member on said collar.

41. In a device of the kind described, a casing, a shaft mounted therein, a die comprising spaced collars embracing the shaft and within which the shaft is rotatable and a die portion having a discharge aperture therein, and means for securing it to the casing, a notching device coöperating with the die comprising a collar on the shaft and rotatable therewith between said spaced collars of the die, and a notching member on said collar.

42. In a device of the kind described, a casing, a shaft mounted therein, a die comprising spaced collars embracing the shaft and within which the shaft is rotatable and a die portion having a discharge aperture therein, a die plate notched over the inner end of said aperture, and means for securing said die portion to the casing, a notching device coöperating with the die comprising a collar on the shaft rotatable therewith between said spaced collars of the die, and a notching member on said collar adapted to engage said notched die plate.

43. In a device of the kind described, a casing, a shaft mounted therein, a die comprising spaced collars embracing the shaft and within which the shaft is rotatable, and a die portion integral with said collars adjustably secured to the casing, a notching device comprising a collar slidable on the shaft and rotatable therewith between said spaced collars of the die, and a notching member on said collar.

44. In a device of the kind described, in combination, a casing, a shaft mounted therein, a die comprising spaced collars embracing the shaft and within which the shaft is rotatable and a die portion having a discharge aperture therein, and means for adjustably securing it to the casing, a notching device coöperating with the die comprising a collar slidable on the shaft and rotatable therewith between said spaced collars of the die, and a notching member on said collar.

45. In a device of the kind described, in combination, a casing, a shaft mounted therein, a die comprising spaced collars embracing the shaft and within which the shaft is rotatable and a die portion having a discharge aperture therein, a die plate

notched over the inner end of said aperture, and means for adjustably securing said die portion to the casing, a notching device co-operating with the die comprising a collar 5 slideable on the shaft rotatable therewith between said spaced collars of the die, and a notching member on said collar of the notching device adapted to engage said notched die plate.

10 46. In a device of the kind described, in combination, a casing, a shaft mounted therein, a die comprising spaced collars embracing the shaft and within which the shaft is rotatable and a die portion, and 15 means for securing the die in adjusted position longitudinally of the shaft, a notching device coöperating with the die comprising a collar slideable on the shaft and rotatable therewith between said spaced 20 collars of the die, and a notching member on said collar.

47. In a device of the kind described, in combination, a casing, a shaft mounted therein, a die comprising spaced collars embracing the shaft and within which the shaft is rotatable and a die portion, and means for securing the die in adjusted position longitudinally of the shaft, a notching device coöperating with the die comprising a collar slideable on the shaft and rotatable therewith between said spaced collars of the die, a notching member on said collar, a support for the casing, and means for adjustably connecting the casing with 35 the support.

48. In a device of the kind described, a casing, a shaft having bearings in the casing, a tubular extension on the casing beyond one of said bearings, a box disposed 40 transversely of said extension and opening thereinto, a pinion on the shaft within said extension, a rack-rod within said box co-operative with said pinion, and a die and a notcher both secured to said shaft and one 45 of them rotatable therewith.

49. In a device of the kind described, a casing, a shaft having bearings in the casing, a tubular extension on the casing be-

yond one of said bearings, a box disposed transversely of said extension and opening 50 therewith, a pinion on the shaft within said extension, a rack-rod within said box co-operative with said pinion, and a die and a notcher both adjustably secured to said shaft and one of them rotatable therewith. 55

50. In a device of the kind described, a casing, a shaft having bearings in the casing, a tubular extension on the casing beyond one of said bearings, a box disposed transversely of said extension and opening 60 thereinto, a pinion on the shaft within said extension, a rack-rod within said box co-operative with said pinion, and a die and a notcher both adjustably secured to said shaft and one of them rotatable therewith, 65 a support for the casing, and means for adjustably securing the casing to said support.

51. In a device of the kind described, in combination, a shaft, a notching member 70 upon said shaft, and a die with which said notching member coöperates, said notching device and die having portions interengaging at all times in the operation of the device.

52. In a device of the kind described, in combination, a shaft, a notching member upon said shaft, and a die with which said notching member coöperates, said notching member and die having interengaging guide 80 portions.

53. In a device of the kind described, in combination, a shaft, a die having a portion in which the shaft has a bearing, a notching member operated by the shaft co-operative with the die, said notching member being guided by said portion of the die in which the shaft has bearing, and said die having another portion engaging the notching member to guide the same. 90

In testimony whereof I affix my signature in the presence of two witnesses.

CHARLES W. GRAHAM.
